UNITED STATES PATENT OFFICE.

RICHARD G. INWOOD AND CHESTER C. CHAPMAN, OF SOUTH BEND, INDIANA, ASSIGNEES
TO NATIONAL WIRE BOUND BOX CO., OF SOUTH BEND, INDIANA, A CORPORATION OF
INDIANA.

MACHINE FOR MAKING WIRE-BOUND BOXES.

No. 913,896.

Specification of Letters Patent. Patented March 2, 1909.

Application filed November 9, 1907. Serial No. 401,522.

To all whom it may concern:

Be it known that we, RICHARD G. INWOOD and CHESTER C. CHAPMAN, citizens of the United States, residing at South Bend, in the county of St. Joseph and State of Indiana, have invented certain new and useful Improvements in Machines for Making Wire-Bound Boxes, of which the following is a specification.

10 Our invention relates to improvements in machines for uniting bodies of assembled members or blanks, or the like, preferably with staples for the purpose of fastening them together, and more especially for stitching or stapling to each other in proper relation the sheets, cleats and binding wires to produce blanks from which wire-bound receptacles, boxes, or other packages are to be constructed.

20 The wire-bound boxes referred to are usually rectangular in shape and having solid ends, the four sides being sheets or strips of thin lumber, or veneer, reinforced with inside cleats, step-mitered together at their ends, 25 and with binding-wires extending around the said four sides.

The principal object of the invention is to provide a machine of novel and improved 30 construction for making, more especially, the reinforced veneer blanks to form the four sides of boxes as above described, which machine shall be of particularly simple and durable construction, easy to operate, and capable of manufacturing the finished blanks 35 with comparatively great rapidity and certainty.

In the operation of our improved machine, in its preferred form, the cleats and sheet, or sheet sections necessary for a complete blank 40 for the four sides of the box when folded, are assembled, one series at a time, in proper relation upon guides which pass beneath the staple forming and driving devices. The cleats and sheets are held in the proper spaced 45 relation between the sections by spacing blocks, which, with the assembled cleats and sheet are caused to slide in the guides beneath the staple drivers, and as each section is stapled the spacing blocks are conducted to a 50 point beneath the front of the machine within easy reach of the operator, whereupon they are again positioned upon the guides the spacer blocks to be used over and over, and requiring the use of but two spacing 55 blocks to a machine. Means are also pro-

vided on the carrier for feeding binding or strengthening wires beneath the staples, to be straddled thereby as they are driven through the sheet into the cleats, and for thrusting such wires ahead in a step by step motion alternating with the operation of the stitching or stapling devices. This is one of the novel features of our invention, as the binding wire, during the operation of stitching or stapling, also serves as a means for feeding each section through the machine after the first staple is driven, as well as the finished sections previously operated upon; thus providing an exceedingly simple and effective automatic feed. In other words the binding wires which form a permanent part of the box sections temporarily serve as a means, in connection with mechanism for positively feeding such wires, for feeding the assembled sections through the machine to be operated upon by the stapling devices.

In the accompanying drawings, Figure 1 is a front elevation of the machine. Fig. 2 is a vertical cross-section taken on a line X-X of Fig. 1. Fig. 3 is an end elevation of the machine. Fig. 4 is a perspective view showing the four sections of a complete box blank before being folded. Fig. 5 is a perspective view of the finished box. Fig. 6 is a perspective view of one of the spacing blocks used to hold the cleats and sheets in proper spaced relation while passing through the machine. Fig. 7 is an end view of the same. Fig. 8 is a fragmentary plan view of one end of the box blank material, together with portions of the guide, the spacing block, and the binding wire in assembled relation. Fig. 9 is a side view of the parts shown in Fig. 8. Fig. 10 is a perspective view of a portion of the guide showing a spacing block slidably mounted thereon.

As illustrated, the machine comprises suitable end standards, 1, adapted to support the operative parts of the machine, and are connected by suitable brace rods 2 and 3. 100 These standards are provided at their upper ends with slots 4 serving as guides for a sliding cross-head 5, carrying parts of a plurality of staple formers and drivers 6. These staple formers and drivers are relatively 105 adjustable for different widths of box blanks, so that each may be properly positioned to drive staples astride the binding wires through the sheet into the cleats. The binding wires intermediate the end wires 110

are not driven into the cleats, but are clinched on the inner sides of the sheets, cleats being used at the ends only as a rule. A stationary cross-head 7 is positioned below the sliding cross-head 5 and connected to the standards 1 and upon which the remaining part of the staple forming and driving devices are adjustably mounted, and coöperate with the aforementioned stapling forming and driving parts, to form the staple and drive the same into the assembled blank material as the latter is fed through the machine. These staple drivers and formers may be of any suitable construction, as they in themselves form no part of the present invention, and a detailed description of the mechanism for forming and driving the staples is not given, it being sufficient to say that the wires from which the staples are formed are fed or supplied from reels, or ready made staples may be fed from a hopper, as may be preferred.

Mounted upon one end of the driving shaft 8 which is journaled in suitable bearings 9, is a power pulley 10. This pulley is loosely mounted upon the shaft and is provided with any suitable positive clutch mechanism 11, which is operable to couple the pulley to the shaft and to release it therefrom. A foot-lever 12 is pivoted at 13 to one of the standards 1 and has its free end connected to the free end of a tripping bar 14 by a link 15. The bar 14 is arranged to hold the key (not shown) with which the clutch mechanism is closed and disconnected, a helical spring 16 suspended from a bracket 17 and connected to said bar near its free end serving to normally hold the tripping bar elevated. The power shaft is thus only driven so long as pressure is applied to the foot lever 12, which action releases the tripping lever and allows the clutch mechanism to close. Any suitable clutch mechanism may be used, and the particular manner of controlling the same is described only as a preferable form, and operates to retain the machine in operation only so long as the operator retains his foot upon the foot lever, thereby giving him perfect control at all times over the stapling operations.

Mounted upon the drive shaft 8 are eccentrics 18 which are connected to sliding blocks 19 by pitmen 20. These sliding blocks move in the slots or ways 4 in the standards 1 and are partially a continuation of the upper sliding cross-head 5, so that the operation of the eccentrics imparts an up and down movement to said cross-head and the staple forming and driving devices mounted thereon.

Secured to the standards on the front or feed side of the machine is a fixed shaft 21 upon which relatively adjustable brackets 22 are mounted, and carrying upper and lower gears 23 and 24 adapted to mesh with each

other. Formed integral with these gears are feed wheels, the lower one of which is formed with a peripheral groove 25 and the upper one with a peripheral rib 26 which is knurled on its face and extends into said groove and grips the binding wire C, the object of which is to provide a positive feed for such wires, and feeding the same uniformly and accurately in a step by step motion through the guide tubes 27 to a point beneath the staple drivers coincident with the drive of the staples. The smaller gears 24 may be mounted upon eccentric shafts 29 and held in yieldable engagement with the larger or drive gear 23, by contracting springs 30 fixed at their upper ends to the sides of the brackets 22, and their lower ends connected with the free ends of inwardly extending rods 31 carried by said eccentric shafts. This provides a yielding support and permits wire to be fed of varying gage without necessitating readjustment of any of the parts of the feed mechanism.

The feed is controlled by a shaft 28 journaled in the standards 1, which projects through the gears 23 and is provided with a longitudinal slot (not shown) which is engaged by keys carried by said gears so as to impart an intermittent rotary motion thereto and at the same time allow freedom of relative adjustment of the brackets 22 upon which the gears are mounted. The shaft 28 projects beyond the end of machine as at 32 upon the end of which a well known form of ratchet and pawl mechanism 33 is mounted. The pawl is actuated intermittently by a connecting rod 34 pivoted at its upper end to the pawl and at its lower end to the adjacent eccentric 18. The pivotal point of this connecting rod is eccentric to the main driveshaft and designed to give the shaft 28 a partial turn 105 during the upstroke of the eccentric, thus feeding the binding wire during the interval in which the stapling devices are on their upstroke. In other words, causing the feed of the binding wire to alternate with the driving 110 of the staples. A like mechanism 36 as above described for feeding the binding wires may be employed for feeding the stapling wires to the staple forming and driving devices, the intermittent rotation of a shaft 37 115 which actuates the feed wheels, being accomplished by a lever 38 fulcrumed at 39 to a bracket, and provided with an anti-friction wheel 40 which rests upon a cam 41 mounted upon the main drive shaft. The free end of 120 said lever is connected with a pawl 42 mounted upon the shaft 37 adjoining a ratchet wheel 43 by a connecting rod 44. The cam 41 thus imparts an up and down motion to the lever 38 and through its connections to the shaft 37 actuates the stapling wire feeding mechanism 36.

In the assembling of the parts which comprise the box sections, it is necessary to hold these parts in proper relation to each other 130

during the feeding of the same through the machine, and for that purpose we employ two oppositely disposed guide bars, 45. The inner end of these guides are provided with an enlargement 46 to serve as an anvil, being channeled, to fit over a fixed beam 47, to which they may be locked against displacement by set screws 48, the outer ends of the guides 45 projecting beyond the machine and supported intermediate their ends by a cross bar 49. The anvil part of these guides are positioned directly below the point at which the staples are driven. The binding wires intermediate the end wires are straddled by the staples which are driven through the sheet and upset or clenched by the staple ends coming in contact with an anvil 50 adjustably mounted upon the supporting beam 47, as no cleats are used at the center of the sheets. The guides 45 are slideable upon their supports 47 and may be relatively adjusted for different widths of box blanks. The guides are provided with spaced ribs 51 and 52 extending upwardly from their base, forming a channel into which the cleats are placed and held against lateral displacement. The base of each guide extends beyond the rib 52 thereof and serves as a seat upon which a spacer block for spacing the cleats endwise may rest. The spacing blocks are each formed in two portions 53—54 separated by a guide way, the portion 54 bearing in the channel between the ribs 51 and 52 and the portion 53 bearing upon the base of the guide at the opposite side of the rib 52, with the separating guide way bearing over the rib 52. The portion 53 is longer than the portion 54 and thus provides a relatively long bearing surface upon the base 45 and thus materially increases the steadiness of the movement. The portion 54 is also formed with reversely inclined faces 55 against which the ends of the cleats A abut. The portions 53 are also each provided with an upright pin 56 which serves to space the ends of the veneer sheets which form the box sides in proper relation to each other, so that they will not bind when folded. The pins 56 being located in the portions 53 of the blocks do not interfere with the binding-wires or the action of the stapling-mechanism. Located beneath the guides 45 and suitably supported, is an inclined chute 57, its upper end extending slightly beyond the inner end of the guides, to receive the spacing blocks as they fall from the guides and conduct them by gravity to a point convenient to the operator. A platform or table 58 may also be employed to receive the finished box blanks, an open space between the inner ends of the guides and the table being provided to permit the spacing blocks to drop into the aforementioned chute.

The operation of the machine is substantially as follows: The operator may com-

mence, for example, by positioning two pairs of the cleats in the channels of the guides 45 with adjacent ends abutting against the sides 55 of the spacing blocks 54. Two sheets of veneer are then disposed upon the cleats with their adjacent edges abutting against the upwardly extending spacing pins 56 on the spacing blocks. The cleats and sheets for the first two blank sections being now assembled in proper relation to each other, the operator manually slides the assembled material forward so as to bring the forward end portion of the same under the stapling devices in proper position to receive the first staples. The binding wires are now advanced so as to rest upon and extend beyond the end of the sheet and coincident with the staples to be driven. The operator now trips the clutch 11 by depressing the foot lever 12, thus setting the drive shaft in motion and causing the staples to be driven astride the binding wires through the veneer sheets into the cleats, and likewise through the sheets intermediate the cleats and "clenching" them upon the anvil member 50. After one operation of the stapling devices the binding wires are firmly attached to the sheet and cleats, and the assembled material of that section of the blank is thereafter automatically fed through the machine by the positive feed of the binding wires which are thrust along by the feed-wheels in a step by step motion alternating in action with the stapling devices. When the last staples are driven into the first blank-section the assembled material for the second section is pushed ahead by the operator, against the intervening spacer blocks, to receive its first staples, after which it also is fed along step-by-step by the intermittently-operating binding-wire-thrusting feed-wheels. The third and fourth blank-sections are assembled and fed along in the same way, the machine being stopped after the last staples have been driven in the blank.

It will thus be noted that an exceedingly simple, effective and novel automatic feeding device is provided, in which the binding wire which forms a permanent part of the box blank, and which is severed as the four sections of the blank are completed, momentarily serves as a means in connection with the wire feeding mechanism to feed the assembled box blank through the machine. As each section of the blank is completed and passes onto the work receiving table, the spacing blocks drop off the end of the guides into the chute heretofore described, to be taken up again by the operator and used over and over, thus requiring but two spacing blocks to a machine. The spacing blocks are also interchangeable and can be used on either guide.

The box blank herein referred to consists of four sections as shown in Fig. 4, and

consists of the cleats A, the sheets B, the binding or reinforcing wires C and the staples D. This blank when folded into rectangular shape forms the four sides of the box. The box ends are nailed or stapled to the inner side of the cleats in any desired manner, the manner of accomplishing which is not a function of the present machine.

Having thus described our invention, what we claim is:

1. In a machine of the class described, a supporting frame including spaced side members, a bar extending between said side members, anvils supported by said bar, guiding means for the assembled blank material and flush with said anvils, spacing members adapted to space the assembled material, means to guide the binding wire on the blanks, stapling devices supported by said frame above said anvils and adapted to staple the binding wire to the blanks, and feeding means for the binding wire, said binding wire operating to feed the blank material and spacing members through the machine.
2. In a machine of the class described, the combination of guiding means for the assembled blank material, means to guide the binding wires on said blank material, means for stapling said binding wires to the blank material, gripping means engaging the binding wire rearwardly of the stapling means, means for operating said gripping means to feed the wire through the machine, the wire operating to feed the blank material through the machine.
3. In a machine of the class described, a supporting frame, anvils supported on the frame, guiding means for the assembled blank material and flush with said anvils, spacing members adapted to space the assembled material, means to guide the binding material on the blanks, stapling devices supported by said frame above said anvils and adapted to staple the binding wire to the blanks, and means for feeding the binding wire through the machine, the binding wire operating to feed the blank material to the machine.
4. In a machine of the class described, the combination of guiding means for the assembled blank material, means for stapling binding wire to the blank material, feeding means operating on said binding wire, and a guiding means for the binding wire curving adjacent to the material to guide the binding wire into position upon the blank material, the binding wire operating to feed the material through the machine.
5. In a machine of the class described the combination of guiding means for the assembled blank material, spacing members adapted to space the assembled material in proper relation, means for feeding said blank material and spacing members through the machine, and means independent of the

spacing members to receive and return said spacing members to the feed side of the machine.

6. In a machine of the class described, guiding means for the assembled blank material, spacing members adapted to space the assembled material, means for guiding the binding wires on the blanks, stapling devices for stapling the binding wires on the blanks and means for feeding the binding wires forwardly in a step by step motion alternately in action with the stapling devices, the binding wires operating to feed the blank material through the machine.

7. In a machine of the class described, stapling devices, guiding means for the assembled blank material, spacing members adapted to space the assembled material, and to drop below the guides as the material is fed forwardly, means for guiding the binding wire upon the blank material, means for securing the binding wire to the material, means for feeding the binding wire, said binding wire operating to feed the blank material and spacing members through the machine, and means for returning said spacing members to the feed side of the machine.

8. In a machine of the class described, stapling devices, guiding means for the assembled blank material, spacing members adapted to space the assembled material, a receptacle beneath said guiding means and inclined towards the feed end of the machine, means for feeding the assembled material and spacing members to the machine and permit the spacer members to drop from the blank material and into said receptacle.

9. In a machine for making wire bound box blanks, means for guiding the blanks through the machine, means for guiding the binding wire upon the assembled blanks, means for securing said wire to said blanks and means for feeding the binding wire, the binding wire operating to feed the blank material through the machine.

10. In a machine for making wire bound box blanks, means for guiding the blanks through the machine, spacing members adapted to space the assembled blank material, means for guiding the binding wire upon the assembled blanks, means for stapling the binding wire upon the blanks, means for feeding the binding wire, said binding wire operating to feed said blank material and spacing members through the machine, and means for returning the spacing members to the feed side of the machine.

11. In a machine of the class described, stapling devices, anvils spaced from said stapling devices, guiding means for the assembled blank material flush with said anvils and at one side thereof, a table at the other side of said anvils and spaced therefrom, a receptacle beneath the space between said table and anvils, spacing blocks between the confront

ing ends of said assembled blank material and adapted to drop into said receptacle as the blank material passes from the anvils to the table.

- 5 12. In a machine of the class described, stapling devices, anvils spaced from said stapling devices, guiding means for the assembled blank material flush with said anvils and at one side thereof, a table at the 10 other side of said anvils and spaced therefrom, spacing blocks between the confronting ends of said assembled blank material and adapted to drop between the anvil and table as the blank material passes thereover.
- 15 13. In a machine for making wire-bound blanks, by stitching together sheets or strips, cleats and binding-wire in the manner set forth, the combination with the stitching-mechanism of means for moving the assembled blank-material across the stitching-mechanism comprising binding-wire engaging and thrusting feed-mechanism with 20 means for guiding the binding-wire therefrom upon the blank-material.
- 25 14. In a machine for making wire-bound blanks, by stitching together sheets or strips,

cleats and binding-wire in the manner set forth, the combination with the stitching-mechanism of means for moving the assembled blank-material across the stitching-mechanism comprising intermittently-operating binding-wire-thrusting feed-mechanism with means for guiding the binding-wire therefrom upon the blank-material. 30

15. In a machine for making wire-bound blanks, by stitching together sheets or strips, cleats and binding-wire in the manner set forth, the combination with the stitching-mechanism of means for moving the assembled blank-material across the stitching-mechanism comprising binding-wire engaging and thrusting feed-mechanism and binding-wire guide-tube extending between said feed and stitching-mechanisms and terminating close to the path of said material. 35

In testimony whereof we affix our signatures, in presence of two witnesses.
